HERMAN HANSON INVENTOR.

BY
Richard B. Owen
ATTORNEY.

UNITED STATES PATENT OFFICE.

HERMAN HANSON, OF GARFIELD, MINNESOTA.

WEEDER AND PULVERIZER.

1,420,698.

Specification of Letters Patent. Patented June 27, 1922.

Application filed October 1, 1921. Serial No. 504,818.

To all whom it may concern:

Be it known that I, HERMAN HANSON, a citizen of the United States, residing at Garfield, in the county of Douglas and State 5 of Minnesota, have invented certain new and useful Improvements in Weeders and Pulverizers, of which the following is a specification.

This invention relates to a weeder and 10 pulverizer attachment for cultivators and has for its principal object to provide a device of this nature which will be efficient and reliable in operation and will be readily placed in and out of engagement with the 15 ground when so desired.

Another object of the invention is to provide simple and efficient means for attaching the device to a cultivator of conventional construction, said attaching means being adjustable so as to accommodate the various 20 differences found in conventional cultivators.

With these and numerous other objects in view the invention comprises certain novel features of construction and the arrangement and combination of parts as will be 25 hereinafter more fully described and claimed.

In the drawings:—

Figure 1 is a plan view of the device showing the same attached to a portion of a 30 cultivator;

Figure 2 is a fragmentary side elevation of the rear portion of the device;

Figure 3 is a longitudinal vertical section taken through the device; and,

Figure 4 is an enlarged section taken on the line 4—4 of Figure 1 looking in the direction of the arrow.

Referring to the drawing in detail it will be seen that 1 designates a cultivator of conventional construction which is usually provided with the rear diverging arms 2 and as is well known the angle formed by these diverging arms 2 varies considerable in various cultivators now commonly in use and 45 it is the purpose, therefore, of the present invention to provide an attachment which is capable of being secured to practically all conventional cultivators having a portion somewhat similar to that illustrated to advantage in Figure 1.

This attachment consists of the beam 3 having fixed thereto a plurality of curved fingers 4 each of which is provided with a shank 5 bent in L-shape so as to fit over the 55 top of the beam 3 and along the forward side thereof. These shanks 5 are held in

place by means of eye bolts 6 which pass through the beam 3. U-shaped rod 7 is fixed to each end of the beam 3 by having one leg thereof riveted to the terminals of 60 the beam as shown at 8 and the other leg 9 projecting a short distance into the beam if so desired. A coil spring 10 is disposed on the rod 7 and has for its purpose to normally keep the attaching means to the extreme outer ends of the beam 3.

The attaching means at each end of the beam 3 is pivotally mounted on the rods 7. Each attaching means consists of a pair of hinged leaves 12 and 13. The leaf 12 is 70 provided with a longitudinally extending slot 13 and an eye 14 for receiving the rod 7. The leaf 13 is provided at its terminal with a suitable eye which is in engagement with an eye 17 carried on a brace rod 18. 75 The other end of the brace rod 18 is provided with an aperture for receiving the bolt 19 which passes through the slot 13 and thus the angle between the leaves 12 and 13 may be varied to accommodate the 80 angle of the diverging arms 2. It will furthermore be seen that the attaching means is adjustable longitudinally of the beam 3 since the spring 10 may be compressed for this purpose.

By having the rods 7 passing through the apertures 14 it will be noted that the beam 3 is therefore pivotally mounted and the fingers may be raised and lowered from engagement with the ground. In order to 90 facilitate the moving of these fingers, I have provided a bracket 20 provided with the upstanding arm 21 and the depending arm 22. This bracket is firmly held in engagement with the beam 3 in any suitable manner and 95 the depending arm 22 is attached to a coil spring 23 which is also attached to a bar 24 or any other suitable part of the cultivator 1 for the purpose of normally holding the fingers in engagement with the ground. 100 A flexible member 25 is provided with a snap hook 26 at its end and is suitably attached to the upstanding arm 21 whereby this flexible member may be pulled toward the cultivator so as to rotate the beam thereby lifting the fingers 4 out of engagement with the ground at the same time expanding the coil spring 23 and the snap hook 26 may be placed in engagement with any portion of the cultivator so as to keep the fingers 4 110 out of engagement with the ground as long as desired.

From the foregoing description taken in connection with the accompanying drawing, the construction and the operation of the attachment will be readily understood without 5 more extensive explanation. As numerous changes in form, proportion and the minor details of construction may be resorted to without departure from the spirit of this invention, I do not wish to limit the construction herein shown and described other 10 than as claimed.

Having thus described my invention what I claim as new is:

1. In combination, a cultivator provided 15 with rearwardly extending diverging arms, an attachment therefor consisting of a beam, U-shaped rods secured to the ends of the beam, springs mounted on the rods, attaching means pivotally mounted on the rods 20 and including a pair of hinged leaves one of which being provided with a slot, means for

attaching the other leaf rigidly to the arms of the harrow, a brace rod pivotally mounted on the last mentioned leaf, and a bolt passing through the slot of the other leaf 25 and the brace rod so as to regulate the angle between the two leaves of each attaching means.

2. An attaching means for agricultural implements of the class described comprising a pair of hinged leaves, one leaf provided with a longitudinally extending slot, the other leaf provided with an extension, a brace rod pivotally mounted on the extension and means movable in the slot for engaging the other end of the brace rod. 30 35

In testimony whereof I affix my signature in presence of two witnesses.

HERMAN HANSON.
